[57] CLAIM

The ornamental design for a leg exerciser, as shown and
described.

DESCRIPTION

FIG. 1 is a perspective view of a leg exerciser showing
my new design;

FIG. 2 is a left side elevational view thereof, the side
opposite being substantially a mirror image;

FIG. 3 is a top plan view thereof;

FIG. 4 is a rear elevational view thereof;

FIG. 5 is a front elevational view thereof; and,

FIG. 6 is a bottom plan view thereof.
